[57] CLAIM

The ornamental design for a combined mailbox and
signal, as shown and described.

DESCRIPTION

FIG. 1 is a top, front, left side perspective view of a
combined mailbox and signal showing my new design;

FIG. 2 is a front elevation thereof;

FIG. 3 is a left side elevation thereof;

FIG. 4 is a rear elevation thereof;

FIG. 5 is a top plan view thereof;

FIG. 6 is a right side elevation thereof; and

FIG. 7 is a perspective view thereof with the signal
shown in a released position.

The undisclosed bottom portion is plane and unornamented.

Fig. 1.
